SPINNING BATH TANK

Robert Hème de Lacotte and Eugène Colombe,
Paris, France, assignors to Comptoir Des Tex-
tiles Artificiels, a corporation of France

Application June 2, 1947, Serial No. 751,950
In France May 22, 1945

Section 1, Public Law 690, August 8, 1946
Patent expires May 22, 1965

6 Claims. (Cl. 18—8)

1

This invention relates to spinning bath tanks used in the production of artificial filaments and yarns. More particularly, it relates to a spinning bath tank particularly suitable for use in the production of yarns to be converted into staple fiber.

In the most frequently employed process of producing staple fiber, a viscose spinning solution was spun through spinnerettes provided with a very large number of orifices into a spinning bath, and the freshly spun filaments were caused to travel through such bath until completely coagulated and regenerated. The filaments, preferably prior to withdrawal from the spinning bath, were condensed without twisting to form a bundle which, upon withdrawal from the bath, were subjected to appropriate treatments and thereafter transversely cut into staple. Alternatively, the bundle of filaments, upon withdrawal from the spinning bath, was collected on an appropriate collection device and thereafter cut into staple which was subjected to the appropriate liquid treatments.

During coagulation, the action of the spinning bath must be as uniform as possible since the filaments at that time are exceedingly delicate. Eddies in the bath tending to separate the filaments and produce tension effects are apt to diminish the quality and even break the filaments.

Most frequently, the spinning bath tank was provided with a plurality of spinnerettes arranged in a straight line or along a curved arc, and the filaments formed by each of these spinnerettes were condensed together by passage through a condensing or converging device. Generally, the spinning bath was introduced in the neighborhood of the spinnerettes and was circulated so that it traveled in the same direction as the filaments.

According to one procedure for the circulation of the spinning bath, the bath was discharged from the tank in the vicinity of the condensing device, and the discharged bath was regenerated in any appropriate manner and then reused. According to another procedure, a large excess of the spinning bath was utilized and an appreciable fraction of the bath discharged from the tank was remixed with fresh spinning bath solution. This second procedure offered the advantage of insuring a more constant composition of the bath and a more uniform coagulation of the viscose due to the fact that the viscose yarns were immersed in a flowing bath of substantially constant composition and which was continuously renewed. However, such procedure tended to produce eddies which were detrimental to the yarn.

2

In the case of spinning cuprammonium cellulose solutions, or even viscose, by the process wherein funnels of the Thiele type were utilized, an eddyless circulation of the bath in the funnels was obtained but the problem in such processes was less complicated inasmuch as the rates of flow involved were considerably lower in small-size apparatus adapted for the production of fine-filament yarns.

10 An object of this invention is to provide a new and improved spinning bath tank.

Another object of this invention is to provide a spinning bath tank in which a portion of the spinning bath is mixed with fresh spinning bath without the production of eddies.

An additional object of this invention is to provide a spinning bath tank wherein a portion of the spinning bath and fresh spinning bath are caused to travel through the tank and the production of eddies inhibited by devices canalizing the flow in parallel streams.

Other and additional objects will become apparent hereinafter.

The details of the invention will be more clearly understood by reference to the following description when taken in connection with the accompanying drawings illustrating a spinning bath tank constructed in accordance with the invention, and wherein:

30 Figure 1 is a longitudinal section of the tank;
Figure 2 is a front elevation, partly broken away, of the tank shown in Figure 1; and
Figure 3 is a plan view of the tank.

Referring now to the drawings wherein like reference numerals designate like parts, the spinning bath tank is formed with side walls 1, a bottom 2, a front wall 3, and a back wall 4. As shown in Figure 3, the walls 1 diverge outwardly in the direction away from the front wall 3, whereby the tank is generally in the form of a trapezoid, the smaller end of which constitutes the front of the tank.

The tank is sub-divided into four compartments, generally designated by the reference numerals 5, 6, 10 and 12 respectively. The compartment 5, which is adjacent the lower rear end of the tank and extends over the entire width of the tank, constitutes the inlet to the tank for fresh spinning bath solution. Spinnerettes 7 are disposed in the top compartment 6, which is separated from the lower compartment 5 by means of a horizontal partition 9. Compartment 6 communicates at its lower end with compartment 5 through an opening 8 extending over the entire width of the tank in the partition 9. A horizontal

partition 14 on the same level as the partition 9 divides the tank into the compartments 10 and 12. The upper forward compartment 10 is separated from the compartments 5 and 6 by means of a vertical partition 11 which terminates at a level sufficient to permit the travel of the yarn thereover during its bath travel. The lower forward compartment 12, as will hereafter become apparent, constitutes a return for the spinning bath solution and communicates through an opening 13 in the partition 14 with compartment 10. Compartment 12 is separated from the compartment 5 by a vertical partition 16 which is spaced from the partition 11 so as to provide an opening 15. By this arrangement, the two openings 8 and 15 are disposed adjacent each other.

The fresh spinning bath liquid is fed from a suitable source of supply (not shown) through a pipe 17 at the rear lower part of the tank. The pipe 17 is connected with a vertical chamber 18 through a chamber 19 which is provided with an inclined bottom 20. The top of the chamber 18 constitutes an overflow for the bath liquid supplied thereto and it discharges into a chamber 21 which, at its lower end, discharges into the compartment 5. An inclined wall 22 serves to guide the liquid from the chamber 21 into the compartment 5. A baffle 23 of a width equal to the chamber 19 is provided therein above the mouth of the inlet 17, whereby, when fresh bath liquor is introduced through the pipe 17, it will be subdivided into two directions and directed onto the inclined bottom 20 of the chamber 19.

A perforated plate 24 secured to the bottom of the chamber 18 subdivides the flowing liquid into a plurality of streams and serves to distribute the liquid uniformly over the entire length of the chamber 18.

Openings 25 are provided in the upper part of the rear wall of the chamber 18 to permit the escape of air and also excess liquid. Any excess liquid discharged through the openings 25 is received in a channel 26 having an inclined bottom 27 which leads to a discharge 28. The inclined bottom 27 also serves for removing water utilized for cleaning the spinnerettes 7 when the machine is not in operation. The rear wall of the channel 26 is provided with a bracket 29 which serves as a support for the spinnerette holders 30.

The vertical wall 14 separating the compartments 6 and 10 is provided on its upper edge with an oblique comb in order to insure a clear separation of the bundles of filaments extruded from each of the spinnerettes without obliging them to change their path. All the bundles travel through the compartment 10 in straight lines converging toward a triangular notch 32 on the upper part of the front wall 3 of the tank and which constitutes a discharge opening for the bundles. The notch 32 also constitutes a condensing or converging guide for the bundles.

The bath liquor passing through the notch 32 is received in a chamber 33 secured to the front wall 3. The chamber 33 is provided with an outlet 34 whereby the liquid is discharged. Means not shown are utilized to feed such discharge liquid to an appropriate reservoir.

Baffles, or converging vertical partitions, 35 are disposed in the lower compartment 12, and parallel vertical partitions 36 and 37 provided respectively in the compartment 5 and the chambers 21 and 18 separate the flowing bath into a number of streams, thereby reducing the turbulence of the flow.

It will be noted that the construction provides

a flow of the bath liquor in parallel streams in the tank, which is as calm as possible and in accordance with the path indicated by the arrows in Figure 1. It will also be observed, that two streams are produced, one of the fresh bath liquor supplied from the compartment 5, and the other formed by a large excess supplied from the return compartment 12 through the opening 15. These two streams create above the partition 11 two adjoining streams directed toward the line of spinnerettes. Under an action of a veritable aspiration produced by the motion of the filaments issuing from the spinnerettes the two streams will be caused to suddenly change their direction of flow; whereupon the two streams will be mixed. The filaments will be thus enveloped by the horizontal moving bath, insuring coagulation and regeneration of the yarn.

The return flow of the bath in the compartment 12 should be sufficiently slow so as to permit ascension of small gas bubbles created through the action of the bath upon the yarns in such a way that the bath escaping from this compartment through the opening 15 toward the spinnerettes 7 does not contain any bubbles, since the latter are apt to have a detrimental effect on the delicate fibers due to the fact that they would penetrate into the yarns by a suction effect and create a large bubble inside the yarns with deleterious results, such as destroying the equilibrium in the filament formation, obstructing numerous orifices in the center of the spinnerettes, as well as clogging the orifices. Whenever small bubbles are formed they have time enough to ascend to the partition 14 and there form a gaseous layer over the liquid and be eliminated in the form of large bubbles through the opening 15, whereupon they will rise toward the bath surface in the compartment 6 at a place where such bubbles are harmless to the spinnerettes.

The condensed bundle of filaments after passing through the notch 32 is passed through baths for appropriate treatment, and then cut into staple. Alternatively, the bundles are directed upon leaving the notch 32 to a suitable collection device, after which the filaments are cut into the desired size and thereafter subjected to the desired liquid treatments.

Any of the known means for imparting the desired bath travel to the filaments in the spinning bath tank can be used. Likewise, any desired guides for maintaining the filaments submerged in the spinning bath can also be used.

A plurality of spinnerettes can be used and the filaments produced by each of the spinnerettes can be condensed to form a large bundle of un-twisted yarns, as hereinbefore described.

The tank can also be provided with appropriate drains whereby such tank can be completely emptied.

Since it is obvious that various changes and modifications can be made in the above description without departing from the nature or spirit thereof, this invention is not restricted thereto except as set forth in the appended claims.

We claim:

1. A spinning bath tank comprising a horizontal partition dividing the rear portion of said tank into an upper rear compartment and a lower rear compartment communicating at their forward ends, spinnerettes disposed in said upper rear compartment, means to supply fresh spinning bath to said lower rear compartment, a second horizontal partition disposed at approximately the same level as the first-named hori-

zontal partition dividing said tank into an upper forward compartment and a lower forward compartment, said second horizontal partition having an opening at its forward end whereby said upper and lower forward compartments communicate with each other, a vertical partition cooperating with said second horizontal partition and spaced forwardly of said upper rear compartment, said vertical partition terminating at its top below the path of travel of the filaments extruded from said spinnerettes, and a second vertical partition separating the two lower compartments, said second vertical partition being spaced from said second horizontal partition to provide an outlet therebetween.

2. A spinning bath tank as set forth in claim 1 wherein the second vertical partition is between the lower compartments and in spaced relationship with respect to the horizontal partitions.

3. A spinning bath tank as set forth in claim 1 wherein the first vertical partition carries a comb for directing the filaments.

4. A spinning bath tank as set forth in claim 1

5
10

wherein the side walls converge toward the front thereof.

5. A spinning bath tank as set forth in claim 1 wherein the means for supplying the fresh bath comprises a pipe connected to the inclined bottom of a chamber, a baffle adjacent the mouth of said pipe to divide the fresh bath fed by said pipe and direct it over said inclined bottom, a second chamber connected to the first-named chamber, a distributor between said chambers, and means to direct the fresh bath liquid from said second chamber to the lower rear compartment.

15 6. A spinning bath tank as set forth in claim 1 wherein the upper and lower rear compartments are provided with vertical partitions and the lower forward compartment is provided with partitions converging in a direction toward the front thereof.
